HERMANN STELZNER, OF LÜBECK, GERMANY, ASSIGNOR TO THE FIRM OF DRÄGER-WERK, HEINR. & BERNH. DRÄGER, OF LÜBECK, GERMANY.

DIVING-HELMET.

1,209,224.

Specification of Letters Patent. Patented Dec. 19, 1916.

Application filed August 26, 1916. Serial No. 117,040.

To all whom it may concern:

Be it known that I, HERMANN STELZNER, a citizen of the German Empire, residing at Lübeck, in the German Empire, have invented certain new and useful Improvements in Diving-Helmets, of which the following is a specification.

The present invention relates to improvements in diving-helmets.

10 The objects of my improvement are, first, to give the helmet such form and configuration that the points of connection or respectively the connecting means for the flexible pipe-conduits or tubes, telephone-cables and 15 the like are reliably sheltered or protected from external influences and are prevented from coming in collision with or being caught by hooking on surrounding objects; and, second, to provide means for improving and facilitating the fastening and joining of the connecting means for the tubes, 20 cables and the like to the helmet.

With this end in view my invention consists in certain novel features of construction and combinations of parts, as will be 25 hereinafter fully described.

I attain the said objects by the means illustrated in the accompanying sheet of drawings in which—

30 Figure 1 is a rear view of a diving-helmet constructed in accordance with and embodying my invention; Fig. 2 is a vertical section on the line A—B of Fig. 1; and Fig. 3 is a plan of the helmet seen from below after 35 the removal of the tubes and telephone cable.

Similar letters refer to similar parts throughout the several figures.

The rear wall of the helmet *a* is provided 40 with an inverted offset *a*³ so that the lower wall portion *a*¹ recedes or is set back from the upper one *a*² and an external recess is formed in the rear of said helmet. The said offset *a*³ is greatest in the vertical mid- 45 plane of the helmet and decreases in area toward the sides of the helmet so that the horizontal wall *a*³ forming the offset between the wall portions *a*¹ and *a*², when seen from below, presents a sickle- or crescent-shaped surface; (Fig. 3).

To the wall or offset *a*³ are attached the connecting means such as branches *d* *d*¹ for the tubes *s* *s*¹, a nipple *t*¹ for the telephone-cable *t* and the like which connecting means

are thus located entirely within the external 55 recess formed by the walls *a*¹ and *a*³, in protected positions. The joining of the connecting branches *d* *d*¹ to the wall *a*³ is preferably effected by means of a connecting piece *c* having holes into which the said 60 branches *d* *d*¹ are firmly and tightly secured. The connecting piece *c* is screwed against the offset *a*³ by a screw bolt *b* passed from the interior of the helmet through a hole in the wall or offset *a*³ and engaging a screw 65 threaded bore in an enlarged part or bulb *c*¹ of the piece *c*. As the said bore does not fully traverse the connecting piece *c*, no special means are necessary for tightening or packing the head of the bolt *b*. A sufficient 70 air and watertight connection is already secured by a suitable washer plate *e* placed between the piece *c* and the offset *a*³. The holes of the piece *c* or respectively the openings of the branches *d* *d*¹ fastened therein 75 register of course with corresponding holes in the offset *a*³. The free angular space produced by the offset *a*³ within the helmet may be used for arranging a suitable air channel or channels *f* leading from the rear to 80 the front of the helmet, (Fig. 2).

It is obvious that by the sheltered disposition of the connecting means for the helmet-fittings under the offset *a*³ and in the external recess formed thereby, the said connecting means do not project beyond the body of the helmet. Damaging or breaking off of the connecting means by external objects coming in contact or collision with the diving element is therefore substantially ob- 90 viated as well as an entangling of the said connecting means with such objects.

I claim:

1. A diving helmet having a portion of its rear wall extending inwardly to form an 95 external recess and connecting means for attaching helmet fittings to said helmet carried by said inwardly extending offset so as to be located within said external recess.

2. A diving helmet provided in its rear 100 wall with an inwardly extending offset decreasing in area toward the sides of said helmet and forming an external recess and connecting means for attaching helmet fittings to said helmet carried by said inwardly 105 extending offset so as to be located entirely within said external recess.

3. A diving helmet provided in its rear

wall with an offset forming an external recess, connecting means for attaching helmet fittings to said helmet located entirely within said external recess and a connecting member detachably secured to said offset whereby said connecting means are fastened in operative position.

4. A diving-helmet having an inverted offset in its rear wall in combination with a connecting piece adapted to carry suitable connecting means for helmet-fittings and screwed against the said offset from the interior of the helmet by means of a screw-bolt passing through a hole in the wall of

the offset and engaging a screw-threaded bore in the said connecting piece.

5. A diving helmet provided in its rear wall with an inwardly extending offset forming an external recess, connecting means for attaching helmet fittings to said helmet carried by said inwardly extending offset so as to be located entirely within said external recess and means coöperating interiorly with said offset to form an internal channel extending from the rear toward the front of the helmet.

HERMANN STELZNER.
